BILLFOLD ADAPTED TO RECEIVE A
REMOVABLE PASS CASE

Douglas J. Breughton, Springfield, Mass., assignor to Buxton, Incorporated, Springfield, Mass., a corporation of Massachusetts

Application August 17, 1949, Serial No. 110,729

1 Claim. (Cl. 150—38)

1 This invention relates to an improvement in billfolds of the type having a flat tubular loop at one end portion for the reception of a removable pass case or the like.

More particularly it relates to an improved intermediate or bridging wall construction for billfolds of the above type.

The principal object of the invention is to provide an intermediate or bridging wall structure which will operate freely even when a pass case, fully loaded, is incorporated with the billfold.

A further object is to provide a construction which, while achieving the first-mentioned advantages provides a free operation of the loop in its pass case carrying function.

In the accompanying drawings,

Fig. 1 is an unfolded view of a billfold embodying the invention;

Fig. 2 is a detail view of the bridging element;

Fig. 3 is a view of the complete billfold in open position; and

Fig. 4 is a view similar to Fig. 3 but with the front wall members cut away.

Referring to the drawings, 1 generally indicates a blank from which the main body of the billfold is folded up. Blank 1 includes a rear wall member 2, panel members 3 and 4 which extend from a bottom edge of the end portions of the rear wall 2. Flap members 5 and 6 extend from the panel members 3 and 4 respectively. If desired, and as shown, a pocket forming member 7 may be provided which extends from the outer end of panel 4 either as an integral extension thereof or as a separate piece cemented to a marginal extension 8 as shown in Fig. 1. Flaps 9 and 10 extend from the ends of the rear wall member 2 adjacent panels 3 and 4 respectively. As shown, panel 4 is provided with a window opening 11 which is covered with a sheet of transparent material 12, but the panel may be variously treated or left plain as desired. The flap 6 is provided with two tongue members 13 and 14 separated by a cut 17 which extends into the body of the flap 6. Flap 5 is provided with similar tongues 18 and 19 separated by cut 20. The flaps 5 and 6 are preferably, although not necessarily, provided with stiffening members 21 which may be formed of paper or plastic sheets cemented to the inner face of the flaps.

The intermediate or bridging wall member 22, as shown in Figs. 2 and 4, comprises a flat piece of leather having a generally rectangular end portion 23, and an opposite end portion 24 which

is cut away at 25 and 26 to form an elongated narrow tongue 27 provided with a head 28. Preferably, the cuts 25 and 26 are so made as to position the tongue 27 slightly above the longitudinal center of the wall member. Portion 23 is provided with a U-shaped cut 29 forming a downwardly extending tongue 30 positioned at the upper outer corner of the portion 23.

The relation of the various elements in the completed billfold is shown in Figs. 3 and 4. The panels 3 and 4 are folded onto the rear wall with the flaps 5 and 6 each folded downwardly between the panel to which it is secured and the rear wall. Member 7, if present, is folded inwardly against the inner face of panel 4. The tabs 13 and 14 are cemented to flap 10 and the latter with the end portions of the tabs 13 and 14 is folded freely inwardly between flap 6 and the panel 4. The end portions of tabs 18 and 19 are folded over on the face of panel 3 and cemented or otherwise secured thereto. Flap 9 is folded over onto the face of panel 3 and secured thereto in any suitable manner as by interlocking the end portion of the flap in slits 31 as shown.

The bridging member 22 is positioned with its end portion 23 between panel 3 and flap 5 and with its end portion 24 between panel 4 and flap 6. The tongue 30 is inserted downwardly through a slit 32 formed in flap 5. The slit 32 is so positioned as to permit some vertical play to the bridging member but to limit the extent of its downward movement sufficiently to prevent bending of the lower edge of the bridging member in the fold at the bottom of the bill compartment. Enough material is removed in forming the legs of the U shape cut 29 and slit 32 is of sufficient length to afford a limited longitudinal movement of the bridging member relative to the flap 5. The free flap 10 is provided with an arcuate slit 33 through which head 28 is inserted to interlock the end portion 24 to the in-turned free flap 10. Slit 33 is of length to permit a rocking movement of the bridging member in the slit and to permit a limited vertical movement of tongue 27 in the slit.

Preferably the upper edge of the rear wall is provided with a downturned finishing edge portion 34 and an upturned finishing portion 35 at the lower edge between the panels. When the finishing portion 35 is present the lower edge of the bridging member is cut away as at 36 to prevent binding of the lower edge.

As will be apparent, an open ended flat tu-

bular loop is formed between panel 4, and the portion 24 of the bridging wall member 22.

As will be further apparent, in the construction as above described and as best illustrated in Fig. 4, the bridging member is connected at one upper outer corner by the tab 30 engaged in slit 32 in the flap 5 while the opposite end of wall 22 is connected by tongue 27 and its head 28 to the flap 10 which is freely folded inwardly between flap 6 and panel 4. The extension of the tab forming slots 17 and 19 into the body of flaps 6 and 5 respectively give a slight flexibility to the flaps 5 and 6 relative to the members to which they are attached so that in addition to the freedom of movement afforded the end portion 23 by tongue and slot connection 30-32 relative to the flap 5 the latter flap has a somewhat flexible connection to the panel. Similarly the tongue and slot connection 27-33 of the portion 24 of the bridging member to the freely inturned flap 10 permits a rocking movement of the end of the bridging member as the portion 23 may rise or fall by vertical movement of the tongue 30 in the slit 32. When a pass case, not shown, is threaded beneath the loop forming panel 4 the load carried by the pass case tends to cause the pass case to tilt outwardly from the top of the loop and the cutting away of the portion 24 at 26 tends to prevent binding of the bridging member when the pass case is loaded. The preferable position of the tongue 27 above the longitudinal center line of the billfold further assures freedom of movement of the bridging member.

The reinforcements 21, when used, tend to con-

fine the relative movement of the parts to the fold lines and prevent undesirable distortion of the flaps and panel members.

What I claim is:

In a billfold of the type having a rear wall and a front wall, the latter including spaced panel members extending from the end portions of the lower edge of the rear wall, said panel members being folded upwardly onto the rear wall and being provided at their upper edges with panel flaps folded downwardly between the adjacent panel member and the rear wall, end-flaps extending from each end edge of the rear wall, the end-flap at one end of the billfold being folded onto the outer face of the adjacent panel and secured thereto, the end-flap at the opposite end of the billfold being folded freely between the adjacent panel and the panel flap carried thereby; a bridging member having its end portions extending between the panel members and their respective panel flaps, that end of the bridging member adjacent the secured end-flap being provided adjacent its upper outer corner with a U-shaped cut forming a downwardly extending tongue, the adjacent panel flap being provided with a horizontal slit into which said tongue extends, that end of the bridging member adjacent the free end-flap being reduced in width to form a narrow headed tongue, the free end-flap being formed with a transverse slot in which the head of said tongue is interlocked.
